LADDER BRACE

Edmund C. Rein, New Baltimore, Mich.

Application June 12, 1948, Serial No. 32,651

7 Claims. (Cl. 228—60)

1

This invention relates to ladder braces, such as resist slipping of the lower ends of ladders, thus serving as safety devices.

An object of the invention is to adapt a ladder brace for ready adjustment to vary its angular relation to a ladder, being thus suited to different ladder inclinations.

Another object is to adapt a ladder brace to be readily attached to various widths and types of standard ladders.

Another object is to adapt a ladder brace to be quickly shifted to and from a stored position in which it fits compactly between the ladder uprights.

Another object is to provide a novel latching device adapted to securely maintain said stored position of the brace.

Another object is to equip a ladder brace with a shoe having two types of seating faces and a provision for readily bringing either of such faces into use according to the nature of the surface seating the shoe.

Another object is to provide for applying a pair of braces to the lower section of an extension ladder, without interfering with compact stacking of the sections, one on another, when not in use.

These and various other objects are attained by the construction hereinafter described and illustrated in the accompanying drawings, wherein:

Fig. 1 is a longitudinal vertical sectional view of the lower portion of a ladder equipped with my improved brace showing one of the selective inclinations of the ladder afforded by the brace.

Fig. 2 is a similar view showing a stored position of the brace.

Fig. 3 is a view similar to Fig. 1 but showing a different inclination of the ladder.

Fig. 4 is a cross sectional view of one of the ladder rails, taken on line 4—4 of Fig. 2, and showing the stored brace.

Fig. 5 is a fragmentary front elevational view of a ladder equipped with a pair of my improved braces, showing their stored positions.

Fig. 6 is a sectional view taken on the line 6—6 of Fig. 5, and particularly showing latching means to maintain the stored position of a brace.

Fig. 7 is an exploded view of a shoe for attachment to the prop member of the improved brace.

Fig. 8 is a side elevational view of the shoe, showing its toothed metallic elements in a functioning position.

Fig. 9 is a similar view showing a friction block element of the shoe in functioning position.

In these views, the reference character 1 designates the rails and 2 the rungs of an ordinary wooden ladder, the lower portions of the rails having a slight downward divergency, as best

2

appears in Fig. 5, this being common practice. Said ladder is equipped with a pair of my improved braces, each comprising a prop 3 of channel bar form and a link 4 also formed by a channel bar, mounting the prop on a rail of the ladder. The width of the link 4 is slightly less than that of the prop, whereby the link fits between the flanges of the prop in engaging the latter, and may be stored substantially between said flanges, when desired, as best appears in Figs. 2, 4 and 6. The channels formed by the prop and link are relatively reversed, their flanges projecting toward each other. A pin 5 pivotally connects each prop to the corresponding link. The pivotal connection of each link to the corresponding rail 4 is established by a bolt 6, headed as indicated at 7 against a washer 8 engaging the outer face of the rail. It is preferred to form the washer 8 with prongs 9 which embed themselves in the rails and a similar washer 10 on each bolt engages the inner face of the corresponding rail. The described points of attachment of the links to the rails are preferably about midway between the lowermost rung 2 and the lower ends of the rails. A tube 11 fitted on each bolt abuts the corresponding washer 10 and extends through the flanges of the corresponding link 4. A nut 12 on each bolt 6 clamps washers 13 and 14 against said tube, retaining the corresponding link 4 on such tube while affording it free pivotal play. Preferably the washers 14 are of a split spring type, tending to lock the nuts on their bolts. Each link is spaced inwardly from the corresponding washer 10 by a collar 15 carried by the corresponding tube 11, the purpose of this being hereinafter explained.

The props 3 have corresponding end portions each formed with several notches in its flanges to selectively engage the lowermost rung 2. In the construction illustrated, the props each have three such notches 16a, 16b, and 16c. Use of the notches 16a establishes a minimum deviation of the ladder from the vertical, as per Fig. 1, this being the most commonly required ladder position. A considerably sharper incline results from use of the notches 16b, and a maximum incline from use of the notches 16c (Fig. 3). The other ends of the props carry ground or floor engaging shoes pivoted to the prop flanges by pins 17. Each such shoe comprises a base plate 18 which is substantially horizontal in use and has down-turned opposite margins 19 serrated to increase their resistance to slipping. Each of said margins has its end portions formed with notches 20 between which a tongue is formed for insertion in a slot 21 of a side plate 22. When the shoe is assembled, its side plates straddle the base plate and project above the latter to engage the corresponding pivot pin 17, the prop carrying such

shoe engaging between the side plates thereof. Each shoe further comprises a rubber tread member 23, bonderized or otherwise rigidly mounted on a metal mounting plate 24 projecting beyond one end of said tread member to mount one end of a flat sheet metal spring latch 25 extending from end to end of the plate 24 and sufficiently spaced from the latter to accommodate the plate 18. The fixed end of the latch 25 is preferably welded to the plate 24, the latter having its aforesaid projecting end offset slightly as indicated at 26 to effect the desired spacing of the spring latch and mounting plate. Along its margin remote from its welded end, the latch 25 is bent to form a latch head 27 to snap across an end of the plate 18. Thus the rubber tread 23 may be applied to the shoe either above the plate 18 as per Fig. 8, or below said plate as per Fig. 9, according as it is desired to merely store said tread or put it in use. When above the plate 18, any thrust imposed on the corresponding prop 3 is transmitted through the serrated margins 19 which tend to dig into the ladder-supporting surface to strongly resist slipping. This is desirable when said surface is cement, stone, rough wood, or the like. When, however, a ladder is used on linoleum or any nicely finished surface, the rubber treads 23 are disposed beneath the plates 18 raising the margins 19 clear of said surface and resisting sliding by a high degree of friction. To increase such frictional resistance, the floor-engaging faces of the treads 23 are preferably ridged, as shown. By latching the rubber treads in place, as described, they may be quickly adjusted for use or disuse and are very securely retained in either position.

A very important feature of the invention is its provision for locating the braces against the inner faces of the rails and completely out of the way, when not required. Thus the links 4 have notches 28 so spaced from the rail-engaging ends of the links as to accommodate the lowermost rung when the links are upwardly swung into parallelism with the rails. The props may then be downwardly swung about the pins 5 to straddle the links, notches 29 being so formed in the prop flanges as to accommodate the lowermost rung. Thus in a stored position of the braces, the lowermost rung is engaged between the prop and link of each brace, and the braces lie fully between the planes defined by the front and rear faces of the rails. It is to be observed that the function of the notches 28 and 29 is radically different from that of the notches 16a, 16b, and 16c, the latter functioning only when the braces are in use and the former only when the braces are collapsed.

As a provision for positively maintaining the braces in stored position, a latch member 30 having a latch head 31 is pivoted on each tube 11 midway between the flanges of the corresponding link 4, being held in such mid position by engagement of a lug 32 on the rear end of the latch member in a slot 33 formed in the yoke portion of the link. The latch head is received by a slot 34 of the prop 3, when the latter is in stored position, and an elongated flat spring 35 secured at one end thereof to the latch member bears at its other end on the channel bottom of the link to urge the latch member to latching position. In that position the latch head overlaps an end margin of the slot 33, preventing separation of the prop and link. The headed end of the latch member is rounded to effect retraction of said

member as the prop and link assume their stored position.

It is desirable to allow a slight forward and back play of the ladder relative to the paired braces to permit of such vibration and flexing as commonly occurs, under load. To afford such play the pin 5 interconnecting the link and prop of each brace is received by slots 36 in the prop, elongated along the latter.

10 By equipping a ladder with the described braces, the likelihood of accidents is greatly reduced, and there are made feasible inclinations of the ladder which would be obviously unsafe in the absence of said braces. Provision of the links 4 is a vital 15 feature in adapting the braces to withstand heavy stresses, and said links are further utilized to facilitate collapsing of the braces, when desired and to effect their retention in stored positions. The function of the spacer collars 15 best appears 20 in Fig. 5, which shows that collapsing of the braces would be interfered with by the ladder rails (due to their upward convergency), if the spacer collars were not provided.

Pivotal attachment of the shoes to the props 25 permits the shoes to adapt themselves to various inclinations of the ladder. The alternative seating provisions afforded by the shoes, allow the braces to be adapted to different types of ladder-supporting surfaces, without damage to any 30 thereof, and deriving the most efficient resistance to slipping.

What I claim is:

1. In a ladder brace, the combination with a 35 ladder comprising a pair of rails, of an abutment fixed on one of side rails, a prop notched to detachably engage said abutment, a link bar, and means pivoting the ends of the link bar respectively to said prop and rail, the connection of said bar to the rail being downwardly spaced from said abutment, when the brace is in use, said prop and link bar having a stored position of substantial parallelism with the rails said prop and link bar having channel forms, and being proportioned to fit one within the other in said stored position.

45 2. A ladder brace as set forth in claim 1, said prop and link bar having laterally opening notches jointly accommodating said abutment in the stored position of the brace.

3. In a ladder brace as set forth in claim 1, a 50 latch element for detachably interconnecting said prop and link bar in their stored position, said element being pivoted on one of said parts requiring interconnection, and the other of such parts being apertured to receive such element.

55 4. In a ladder brace as set forth in claim 1, a latch member pivoted on the link bar substantially at its rail connection and detachably engageable with the prop in the stored position of the prop and link bar.

60 5. A ladder brace as set forth in claim 1, said prop having a plurality of notches to selectively receive said abutment in use positions of the prop, and having an additional notch for receiving the abutment in said stored position.

65 6. In a ladder brace as set forth in claim 1, said link bar being swingable about its rail-engaging end to one side of said abutment in assuming said stored position, and said prop being swingable on the link into substantial parallelism with the link at the other side of said abutment, means for detachably latching the rail-engaging end portion of the link bar to the prop to maintain their stored relation to the abutment.

7. In a ladder brace, the combination with a

ladder comprising a pair of rails, of an abutment fixed on one of said rails, a prop notched to detachably engage said abutment, a link bar, an element pivoting one end of said bar to the prop, an element pivoting the other end of said bar to one of the rails, a latch member pivoted on the last-mentioned element to engage the prop, and a spring acting on the latch member to yieldably maintain its engagement with the prop, the prop and link bar having a stored position of substantial parallelism with the rails and said latch element being effective to maintain such position.
